UNITED STATES PATENT OFFICE.

ROSA M. VERNON, OF GAMBIER, OHIO.

DESIGN FOR A KITCHEN WALL-CABINET.

SPECIFICATION forming part of Design No. 36,744, dated January 19, 1904.

Application filed November 5, 1903. Serial No. 179,997. Term of patent 3½ years.

To all whom it may concern:

Be it known that I, ROSA M. VERNON, a citizen of the United States, residing at Gambier, in the county of Knox and State of Ohio, have 5 invented a new, original, and ornamental Design for Kitchen Wall-Cabinets, of which the following is a specification, reference being had to the accompanying drawing, forming a part thereof.

10 In the drawing accompanying this specification and made a part hereof the figure is a perspective view of my kitchen wall-cabinet.

What I claim as new, and desire to secure by Letters Patent, is—15 The ornamental design for a kitchen wall-cabinet, as shown.

ROSA M. VERNON.
